Primary Examiner — Kelley Donnelly

(74) Attorney, Agent, or Firm — Brooks Krushman P.C.;
Lora Graentzdoerffer(57) **CLAIM**

The ornamental design for a color center display array, as shown and described.

DESCRIPTION

FIG. 1 is a front perspective view thereof;

FIG. 2 is a side perspective view thereof;

FIG. 3 is a front elevational view thereof; and,

FIG. 4 is a top plan view thereof.

The broken-line disclosure in the views represents portions of the color center display array in which the claimed design is embodied, but which form no part of the claimed design.
